Primary Examiner — Paula Allen Greene(74) *Attorney, Agent, or Firm* — Alonso & Associates;
Arlyn Alonso(57) **CLAIM**

The ornamental design for a headphone headset, as shown and described.

DESCRIPTION

FIG. 1 is a perspective view of a headphone headset showing my new design, the opposite front face of the interior headphone headset ear cup is a mirror image.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The headphone headset may be used for listening to music and/or audio signals from a transmitting device.
